JARED ROWLAND, OF BROOKLYN, E. D. NEW YORK.

Letters Patent No. 64,710, dated May 14, 1867.

IMPROVEMENT IN LOCKING APPARATUS FOR FERRY-BOATS.

The Schedule referred to in these Letters Patent and making part of the same.

TO ALL WHOM IT MAY CONCERN:

Be it known that I, JARED ROWLAND, of Brooklyn, E. D., in the county of Kings, and State of New York, have invented a new and improved Apparatus for Securing Ferry-Boats to Bridges; and I do hereby declare that the following is a full, clear, and exact description thereof, which will enable others skilled in the art to make and use the same, reference being had to the accompanying drawings forming part of this specification, in which—

Figure 1 represents a vertical longitudinal section of my improved apparatus.

Figure 2 is a bottom view of the same.

Similar letters of reference indicate like parts.

The object of this invention is to arrange a device whereby the engineer or the pilot of a ferry-boat may be enabled to secure the boat to the bridge and to detach the same therefrom, as he may desire. The difficulty hitherto experienced in securing the boat to the bridges and detach the same therefrom, is completely overcome by this invention, as the extra deck-hands for operating the apparatus are not required, my device working automatically.

A represents the deck of a ferry-boat, which is constructed as usual. To the under side of the same are hinged, with each of their ends, iron bars *a a*, one being arranged on each end of the boat. These bars are bent so as to conform and correspond to the shape of the end of the boat, which is generally formed like an arc of a circle. On any convenient part of the boat is arranged a vertical shaft, *b*, with a crank or wheel, *c*, on its upper end, so that it may be conveniently turned in its bearings. On this shaft is firmly secured a wheel or drum, *d*, which turns with the shaft. Chains or ropes *e e* are secured to the circumference of the wheel or drum *d*, their other ends being secured to the bars *a* in such a manner that as the chains are wound around the drum *d*, the bars will be raised to a horizontal position, so that they will lie flush against the under side of the deck, but they will drop to a vertical position as soon as the chains are slackened. By means of a ratchet-wheel, *g*, and pawl *h*, the shaft may be locked so as to retain the bars *a* in any desired position. B is the bridge to which the boat is to be secured; the same is also constructed as usual. To its under side are hinged two or more bars *f f*, their rear or inner ends being weighted, so as to be heavier than their front ends. Their front or outer ends are hook-shaped, with an inclined outer surface, so that as the boat approaches, the bar *a*, being lowered, will come in contact with the incline surface of the hook, and will partly depress the hook, and partly move upon the said incline until it drops behind the projecting portion of the hooks. The boat is then well secured to the bridge, and the bar is well locked, as the upper surface of the hooks is pressed against the lower surface of the deck by means of their weighted inner ends. A recess is provided in the under surface of the deck for the bar *a* to fit in, so that the boat may be detached, by raising the bar *a* in the aforesaid manner, so that it will lie in the recess in the deck. The hooks will then not have any more hold on the bars, and thus the boat is completely detached. If desired, a gong-bell or other apparatus may be connected with the hooks *f*, whereby notice may be given that the boat is secured or detached, as the case may be.

Having thus described my invention, what I claim as new, and desire to secure by Letters Patent, is—

1. The hooks *f f*, arranged on the under side of the bridge B, and weighted at their inner ends, substantially as and for the purpose herein shown and described.
2. The bars *a*, arranged at each end of the boat below the deck, and operated by the shaft *b* and chains *e* substantially as and for the purpose herein shown and described.

JARED ROWLAND.
